UNITED STATES PATENT OFFICE.

FREDERICK STRAHM, OF LAWRENCE, KANSAS.

CAR-SEAL.

1,375,025.

Specification of Letters Patent. Patented Apr. 19, 1921.

Application filed September 18, 1920. Serial No. 411,298.

To all whom it may concern:

Be it known that I, FREDERICK STRAHM, a citizen of the United States, residing at Lawrence, in the county of Douglas, State 5 of Kansas, have invented certain new and useful Improvements in Car-Seals; and I do hereby declare the following to be a full, clear, and exact description of the invention, such as will enable others skilled 10 in the art to which it appertains to make and use the same.

This invention relates to new and useful improvements in car seals.

One object of the invention is to provide 15 a car seal which is automatic in its locking action but which can be readily broken when it is desired to remove the seal, the construction being such that the device cannot be opened without detection.

20 Another object resides in the peculiar manner in which the parts are constructed whereby the ribbon is securely attached to the housing to permit easy insertion of one end of the ribbon into engagement with the locking tongue, and to prevent the parts being 25 separated without the fact being apparent.

Other objects and advantages will be apparent from the following description when 30 taken in connection with the accompanying drawing.

In the drawing:

Figure 1 is a side elevation of the improved car seal.

35 Fig. 2 is a front elevation of the same.

Fig. 3 is an enlarged longitudinal sectional view through the locking portion of the seal, on the line 3—3 of Fig. 2.

Fig. 4 is a transverse sectional view 40 through the locking portion of the device, on the line 4—4 of Fig. 2.

Fig. 5 is a perspective view of the locking portion of the seal, the housing being shown in the position before being crimped 45 around the end of the ribbon.

Referring particularly to the accompanying drawing, 10 represents the ribbon of the seal which is formed from any suitable material, and has an elongated angular opening 50 in one end portion, as shown at 11, while the other end is formed with a similar opening 12. Each end of the ribbon has formed in its opposite edges the notches 13. Formed in the first-named end of the ribbon 10, outwardly of the opening 11, is an 55 elongated opening 14, formed by striking

out the two tongues 15 and 16. The former tongue is shorter than the latter, and both tongues are curved outwardly beyond the upper face of the ribbon, as clearly seen 60 in Fig. 5. The shorter tongue has its free end directed toward the lower face of the free end of the longer tongue for a purpose which will presently appear. Disposed beneath the last-named end of the strip 10 is 65 one wing or leaf of an angular plate 17, said wing having a pair of longitudinal tongues 18 struck out therefrom and passed through the opening 11 and bent down on the upper face of the end of the ribbon 70 10. This holds the end of the strip against detachment from the plate 17. It will be noted that the edge of the wing to which the ribbon is attached extends a short distance beyond the edge of the strip 10. The 75 other wing of the plate 17 is slightly longer than the first-mentioned wing, so that said other wing, when bent down to overlie the end of the ribbon, may have its free edge crimped with the projecting edge of the first 80 wing, as shown at 18'. To distinguish the wings the first is designated as 17' and the second as 17''. The wing 17'', immediately over the bent up tongues 15 and 16, is struck out or pressed out to form an external boss 85 19 and the internal recess receiving the ends of the tongues, as clearly seen in the sectional view Fig. 3.

When the wing 17'' is crimped with the wing 17', the former wing is placed in 90 spaced relation to the adjacent flat face of the ribbon 10 so that there will be formed a slot 21, between the ends of the wing 17'' and the end of the ribbon for insertion of the other end of the ribbon therethrough. 95

When the outer or free end of the ribbon is pushed through the slot 21, into the housing formed by the plate 17, it will flex the longer tongue 16 until the portion of the ribbon having the opening 12 has passed 100 said larger tongue. The end of the longer tongue will immediately snap into the opening 12, and upon pulling the ribbon backwardly to a slight degree, the end of the ribbon will pass between the ends of the 105 two tongues, and said ribbon end engage beneath the shorter tongue. The end of the ribbon is thus secured within the housing, and any attempt to slide the ribbon in either direction will result in the longer tongue 110 passing farther through the opening 12, or the shorter tongue engaging with the end of

the ribbon. Thus the ends of the ribbon are firmly secured within the housing. To remove the seal, the ribbon may be readily torn or broken between the opposite 5 notches 13.

What is claimed is:

A car seal comprising a ribbon having an opening in one end, a pair of struck up 10 tongues in said end outwardly of the opening and extending longitudinally of the strip in overlapping relation, the other end of the ribbon having an opening for the reception of one of said tongues, and a plate bent on its longitudinal median line and

having an opening therein, formed by striking out a pair of tongues which are engaged through the first opening of the ribbon, the longer marginal edges of the plate being crimped together, one wing of the plate having a pressed out recess receiving the ends 15 of the tongues.

In testimony whereof, I affix my signature, in the presence of two witnesses.

FREDERICK STRAHM.
